UNITED STATES PATENT OFFICE.

WALTER M. LIPPINCOTT, OF LYNBROOK, NEW YORK.

INTERNAL-COMBUSTION ENGINE.

1,152,424.

Specification of Letters Patent.

Patented Sept. 7, 1915.

Application filed October 15, 1912. Serial No. 725,828.

To all whom it may concern:

Be it known that I, WALTER M. LIPPINCOTT, citizen of the United States, residing at Lynbrook, in the county of Nassau and State of New York, have invented certain new and useful Improvements in Internal-Combustion Engines, of which the following is a specification.

My invention relates to internal combustion engines of the two cycle type, and particularly to engines of this type having a differential piston whereby a charge is forced into the cylinder under pressure.

The primary and general object of my invention is to improve upon this construction and remove the many objections thereto, and further to provide an engine simple in construction and effectual in operation, and so formed that the charge pumping and compressing chamber shall be directly and immediately connected with the cylinder, thus greatly reducing piping and by-passing and consequent loss of power.

A further object of the invention is to make the parts easily accessible and to provide an engine so constructed that it is only necessary to remove the lower half of the connecting rod bearing and remove the head of the cylinder whereupon the piston may be lifted out through the top of the cylinder leaving the cylinder shell or barrel standing.

Other objects will appear in the course of the following description.

My invention is illustrated in the accompanying drawings, wherein:

Figure 1 is a vertical longitudinal section through a two cycle engine, the piston being at the bottom of stroke the power stroke being completed. Fig. 2 is a like view to Fig. 1 but showing the relation of the parts at the time that the piston is at the upper end of the stroke. Fig. 3 is a sectional elevation of the annular screen surrounding the intake ports of the cylinder. Fig. 4 is a plan view thereof.

Corresponding and like parts are referred to in the following description and indicated in all the views of the accompanying drawings by the same reference characters.

Referring to these drawings, 2 designates the crank case of an engine and 3 the shaft passing therethrough, 4 designating the fly wheel on the shaft. Mounted upon the upper end of the crank case and shown as extending upward therefrom is a cylinder having outer and inner spaced walls design-

nated 5 and 6 respectively, the space between these walls being closed at its upper end by a web 7, the space inclosed by these walls and which surrounds the cylinder constituting a water jacket connected to any source of cold water supply as will be well understood by those conversant with the art.

The inner wall 6 is extended above the web 7 a relatively short distance as at 6^a and is provided with a plurality of intake ports 8. The wall 5 is extended beyond the web 7 as at 5^a to a considerable distance above the upper end of the wall 6^a, and spaced from this wall 5^a is an annular wall 9 which extends downward into the cylinder. This wall 9 it will be observed from Fig. 1 is spaced farther from the wall 5^a than the wall 6 is spaced from the wall 5. The lower end of the wall 9 is provided with compression rings 10. The lower end of the wall 9 it will be seen extends beyond or overlaps the wall 6^a and is spaced therefrom a distance approximately equal to the thickness of the piston wall. The space defined by the lower end of the wall 9 is closed by a head 11 within which is disposed the spark plug 12 which in turn is surrounded by an annular wall 13 spaced from the wall 9, this space forming a water space so as to keep the head of the combustion chamber cool. It will be seen that the space defined by the wall 25, the head 11 and the piston head 18 constitutes this combustion chamber. The lower end of the combustion chamber is provided with ports 24 which extend around the combustion chamber to as great a degree as necessary, and these ports are connected by means of like ports 14 in cylinder wall and ducts 15 to exhaust manifolds 16.

Disposed within the cylinder and reciprocating therein is the piston 17 having the piston head 18, the wrist pin 19 from which extends the connecting rod 20 to the crank 21. The wall of the piston immediately surrounding the head 18 and projecting on each side thereof is thickened as at 22, this thickened portion being provided with exterior compression rings 23 as is usual in pistons of this class. This thickened portion of the wall adjacent to the head 18 is also formed with a plurality of exhaust ports 24, these being arranged circularly around the piston and being adapted to register with the exhaust ports 14 when the piston is at the lower extremity of its movement.

- Above the thickened portion 22 of the piston, the piston wall extends as at 25 fitting the interior wall 6 of the cylinder and being provided adjacent its upper end with intake ports 26 adapted to register with the intake ports 8 of the cylinder wall. The piston wall 25 is of such length that when the piston is in its depressed position as shown in Fig. 1, the upper end of the 5 piston wall will extend above the cylinder wall, and at its upper end the piston wall has an outwardly projecting annular head 27 which extends down over the upper end of the cylinder wall 6^a when the piston is depressed, the outer periphery of the head being formed with compression rings 28 contacting with the outer wall 5^a of the upper portion of the cylinder. This annular head 27 constitutes the charge pumping piston and reciprocates in the space 29 defined by the walls 5^a and 9 and closed at its lower 10 end by the web 7.
- Leading into the lower part of the space 29 which forms the pumping chamber and which is defined by the head 27, the web 7 and the walls 6^a and 5^a, is a by-pass passage or duct 30, 31 leading from a valve chamber 32. This valve chamber is preferably cylindrical in form and disposed therein is a rotary valve 33 so designed as to connect the duct 31 with a duct 34 leading to any suitable carburetor or source of fuel. While I 15 preferably use a rotary valve for cutting off and establishing communication between the carburetor and the charge pumping chamber 29, I wish it distinctly understood that I may use any form of valve for this purpose and that I do not wish to be limited to this particular detail.
- It will, of course, be understood that when the compressing head 27 is moved upward by the upward movement of the piston, the valve 33 will be so disposed as to establish 20 communication between the source of fuel and the space 29, while upon the downward movement of the head 27 and the piston with it, the valve 33 will be so disposed as to cut off said communication, thus permitting the charge to be compressed in the charge 25 compression or pump chamber 29. I have not shown any means for operating the valve 33 as many devices might be used whereby it could be operatively connected to the crank shaft 3 and mechanism for this 30 purpose will be entirely obvious to those skilled in the art.
- The upper end of the space 29 is closed by a head 35 formed by spaced webs 36 and 37 integral with the wall 9, the web being 35 formed with a port 38 opening into the space 29. Above the web 37 an outlet port 40 leads to an adjacent cylinder or to the crank case. A pipe or tube 39 may extend from this port 40 if desired for a purpose 45 to be later stated. By thus connecting the

upper end of the chamber 29, that is, the upper portion of the pumping chamber with the crank case, I not only relieve back pressure in the upper part of the annular space 29 during the up stroke of the head 27, but upon the down stroke of the head 27 oil vapors from the crank case will be drawn 50 into the annular chamber 29, thus aiding lubrication.

Immediately surrounding the intake ports 75 8 and disposed at the lower end of the pumping chamber 29 is a screen 41 of foraminous material. The screen is formed of an intermediate layer of wire gauze annular in form and supported between two 80 angular strips 42 formed with a plurality of perforations making an annular screen to slip over the wall 6^a.

It will be seen that the lower end of the cylinder is formed with outwardly projecting base flanges 43 resting upon flanges 44 formed as part of the crank case and bolted thereto by bolts 45. It will likewise be noted that inasmuch as the flanges 36 and 37 forming the head 35 are integral with the wall 9, 90 the head 11 may be readily removed so as to open the upper portion of the cylinder. This head 35 is held to the body of the cylinder and specifically to the wall 5^a by means of screws 46 or other suitable devices. The 95 space between the wall 13 and the wall 9 as before stated, constitutes a water jacket, and this space is closed at its upper end immediately around the wall 13 but from the space extend pipes 47 and 48 which connect respectively to the radiator and to the 100 water jacket between the walls 5 and 6.

The operation of my engine is as follows. In Fig. 1 the piston is shown as at the lower end of its power stroke and the combustion chamber between the head of the piston and the head 11 is filled with fresh gas. The piston now starts on its return stroke. During the first part of its upward travel, the intake ports 26 and 8 are closed and the exhaust ports 14 and 24 are also closed. The fresh gas between the piston head and the head 11 will be compressed as the piston moves upward. At the same time the pumping head 27 is also carried 110 upward and fresh gas is sucked into the lower part of the annular pumping chamber 29 by the upward travel of the compression head 27. During said upward movement of the head 27 the rotary valve 33 is opened, 115 thus establishing communication between the carburetor and the pumping chamber 29. When the piston has reached the top of its stroke as shown in Fig. 2, the rotary valve is closed and remains closed during 120 the power stroke. When the piston has reached the top of its stroke, the pumping chamber 29 is full of fresh gas and the combustion chamber is full of compressed fresh 125 gas ready for explosion. Ignition and ex- 130

plosion take place and the piston descends on the power stroke. During the descent of the piston, the gas which had heretofore been drawn into the chamber 29 is compressed. When the piston has nearly reached the bottom of the power stroke, the exhaust ports 14 and 24 uncover. These exhaust ports are larger than the ports 8 and 26 and as a consequence they uncover first.

5 The exhaust gas therefore rushes out through the exhaust ports and the cylinder pressure is negative. At this instant the intake ports 8 and 26 uncover or register and the compressed gas confined in the pumping chamber 29 rushes into the combustion chamber from all sides and masses about the spark plug filling the combustion chamber with fresh gas and forcing the remaining dead gas through the exhaust ports.

10 The piston now starts on its return stroke.

15 It will be seen that my improved engine is practically valveless. The rotary valve disposed in the casing 32 is simply for the purpose of allowing the fresh gas to enter the pumping chamber 29 and retaining it there until its transmission into the combustion chamber, the expulsion of dead gas from the combustion chamber and the admission of fresh gas into said chamber being entirely independent of any valve action, there are no valves to be subjected to the hot explosive action of combustion.

20 The annular chamber 29 above the pumping head of the piston may be utilized as a pump chamber, for pumping tires and storing air in tanks for air brakes or for self starting. The valve mechanism whereby this is accomplished is not illustrated in my drawings nor described for the reason that 25 it forms no part of my present invention.

25 While I have illustrated what I deem to be the best form of my invention, I do not wish to be limited thereto as it is obvious that many changes might be made in the 30 detailed construction without departing from the spirit of the invention.

35 What I claim is:

40 In an internal combustion engine, a cylinder forming a combustion chamber, a crank

case at one end of the cylinder into which it opens, the other end of the cylinder being open, an annular wall entering the last named end of the cylinder, a head forming the inner end of said wall, said wall and head being less in diameter than the diameter of the cylinder, the outer end of the annular wall being formed with a laterally extending hollow flanged portion closing the upper end of the cylinder and detachably engaged therewith, said cylinder adjacent the wall being formed with a plurality of intake ports and adjacent the other end of the cylinder with a plurality of exhaust ports, an outer annular wall extending parallel to the wall having the head and the wall of the cylinder, a web intersecting the space between the cylinder wall and the outer wall, the space so defined immediately surrounding the cylinder constituting a water jacket and the space so defined immediately surrounding the annular wall and the head thereof constituting a pumping chamber, said pumping chamber having an intake port, a valve for controlling the inlet of a charge through said inlet port, a piston disposed within the cylinder and having an annular extension fitting the cylinder and projecting through the space formed between the annular wall and its head and the adjacent wall of the cylinder and into the pumping chamber, an annular piston head carried upon said end of the piston extension and operating within the pumping chamber, said piston having exhaust ports adjacent its head and inlet ports adjacent the opposite end adapted to register with the intake ports of the cylinder, and a tubular connection between the hollow flanged portion of the annular wall and the crank case, said hollow flanged portion opening into the pumping chamber.

45 In testimony whereof I affix my signature in presence of two witnesses.
